UNITED STATES PATENT OFFICE.

JOHN C. BOWERS, OF BOSTON, MASSACHUSETT

HERMETICALLY-SEALED RECEPTACLE.

1,161,446.

Specification of Letters Patent. Patented Nov. 23, 1915.

Original application filed November 19, 1908, Serial No. 463,414. Divided and this application filed May 19, 1911. Serial No. 628,279.

To all whom it may concern:

Be it known that I, JOHN C. BOWERS, a citizen of the United States, residing in Boston, in the county of Suffolk and State of Massachusetts, have invented certain new and useful Improvements in Hermetically-Sealed Receptacles, of which the following is a full, clear, and exact specification.

My invention relates particularly to the 10 hermetic sealing of cans, boxes and other receptacles made from sheet metal, wherein the closure is secured to the body portion without the use of solder, and wherein such closure may be removed without the using 15 of a key or other tool.

The invention adapts itself particularly to receptacles made of tin plate.

According to my present invention the outer edges of the seaming flanges are of 20 single thickness. The locking face in the seaming flange is formed by producing a groove in the outer face of one of the seaming flanges and a ridge on the outer face of the other seaming flange and the sealing 25 strip is conformed to the groove and ridge thus formed, so as to provide a tight joint wherein the sealing strip is held firmly in place. The groove and ridge are preferably formed at the time of applying the strip to 30 the sealing flange.

This application is a division of application Serial No. 463,414, filed by me on November 19th, 1908, in which application there is broadly claimed the feature of a pair 35 of single thickness mating indented flanges and a pair of sealing flanges mating therewith.

The present invention is directed to the locking strip engaging an inwardly facing shoulder on each of a pair of single thickness sealing flanges, the sealing strip mating with such flanges.

My application Serial No. 628,280, filed on the date of the filing of this application is 40 also a division of the same parent application in which divisional application there is claimed the feature of having a free edge of the sealing strip seated in a groove in one of the seaming flanges and of one of the flanges 45 of the sealing strip overlying and mating with the seaming flange.

In the accompanying drawing I have shown a practicable embodiment of the invention. In this illustration my improvements are shown applied to a tin box of a kind commonly employed in packing fish,

meat, and the like. This form of receptacle is selected merely for convenience of illustration.

Figure 1 is a perspective view of a tin box 60 or can, the general form of which is well known, but which has my improvements applied thereto. Fig. 2 is a vertical central section of Fig. 1, taken on a plane at about the line 2—2. Fig. 3 is a perspective view 65 of the receptacle showing the sealing strip partly detached. Fig. 4 is an enlarged detail view, in section, showing the seaming flanges of the receptacle and closure with the sealing strip applied thereto, but before 70 the strip and flanges have been bent into their final form. Fig. 5 is a similar view showing the parts after they have been bent into their final form, and, Fig. 6 is a view showing the reversal of the parts shown in 75 Fig. 5, the sealing strip being shown extending inside the rear of the closure.

The box A, is shown having at its upper edge a seaming flange a, projecting outwardly from the box. The closure B, herein illustrated is formed with a central depressed portion b, surrounded by side walls b', which lie close to the vertical walls of the box A, near its upper end, and an outwardly projecting seaming flange b² which 85 surrounds the cover and overlaps the seaming flange a, of the body A.

The manner in which the cover may be applied to the body of the receptacle is illustrated in Fig. 5, the flat face of the flange 90 b² resting on the flat face of the flange a. After the seaming flanges have been superposed one upon the other, a sealing strip D, is removably applied to the seaming flanges. This strip is preferably made of thin malleable metal which may be easily bent and formed into shape, which shape will be maintained during shipment and storage. The strip will be so applied that when it is desired to remove it and force is applied, it 95 will yield and separate from the joint. Upon removal of the strip the closure may then be removed.

The strip D, before being connected with the receptacle, is preferably substantially U-shaped in cross-section and is provided with flanges d, d', between which is a channel to receive the seaming flanges. The arch of the sealing strip in the present illustration covers the free outwardly directed edges of the 110 seaming flanges. The channel is shown sufficiently wide to allow the flanges to enter and

approximately fill it. The strip is made entirely to surround the joint. One end of the strip is shown overlapping the other end, which overlapping may be in the form of a tongue E.

After the parts have been loosely assembled, suitable mechanism, such as properly formed rolls or dies will compress the strip tightly upon the seaming flanges. The rolls or dies, by their formation, will produce in the flanges indentations, producing an inwardly directed shoulder on one flange and a corresponding recess in the other flange. The seaming flanges are indented one into the other and the flanges of the sealing strip into these. The free edges of the superposed flanges are covered by the sealing strip and held in place by the offsets in the flanges, the inward face of the groove and the inward face of the rib which are located inwardly of such edges. The flanges are formed with indentations, flange *a* with a rib producing a shoulder *y*, and a corresponding groove *y'* in flange *b*. By the operation above described, in forming the rib *y* and the groove *y'* in the seaming flanges, the sealing strip is given a similar or corresponding formation; that is to say, it is formed with a shoulder or rib *z*, which enters the groove *y'*, in the seam and a groove *z'*, into which fits the shoulder or rib *y*, on the flange *a*, of the seam. By a single operation between properly formed dies or rolls, the sealing strip is applied to the seaming flanges which are shouldered in such manner as to prevent the strip from accidentally slipping off from the flanges, and also an air-tight joint is made, making the use of solder unnecessary either for sealing or securing purposes.

In Fig. 6 the edge of the sealing strip is bent inwardly at *d''* to overlie the edge or face *b'* of the closure portion and afford an additional locking feature of the device.

Having thus described my invention I claim:

1. The combination with a receptacle provided with an outwardly disposed flange having two zones occupying substantially the same plane and an intermediate groove, of a cover having a recess and a flange mating with the flange of the receptacle, and a fastening member having two united flanges overlying said first mentioned flanges and mating therewith, the edge of one of the fastening member flanges having a transversely disposed edge extending within the recess of the cover.

2. An easily opened air tight receptacle comprising a can body having an outwardly extending flanges about its open end, a cover having a depressed portion fitting within the open end of the can body, and having

a flange adapted to overlie the flange on the can body, and a readily removable sealing strip comprising a thin channel-shaped member of malleable metal inclosing said flanges, one flange of said sealing strip being bent down to form a transversely disposed portion extending within the depressed portion of the cover and engaging the side wall of the same.

3. An easily opened air tight receptacle comprising a can body having an outwardly extending flange about its open end, a cover having a depressed portion fitting in the open end of said can body and having an outwardly extending flange superimposed on the flange of the can body, and a readily removable sealing strip comprising a channel-shaped piece of thin malleable sheet metal embracing said flanges, the flanges on said can body and cover and both flanges of said sealing strip being coincidentally bent to form interlocking shoulders.

4. A seam for receptacles comprising flanges on the receptacle parts and a readily removable sealing strip embracing said flanges, said sealing strip comprising a channel-shaped piece of thin malleable metal, said receptacle flanges and both flanges of said sealing strip being coincidentally bent to form interlocking shoulders to assist in retaining said sealing strip in position.

5. A seam for receptacles comprising flanges of substantially uniform thickness on the receptacle parts and a readily removable sealing strip embracing said flanges, said sealing strip comprising a channel-shaped piece of thin malleable metal, the flanges of said receptacle parts and a flange of said sealing strip being provided with coincident medial grooves forming interlocking parts which assist in sealing the receptacle and holding the sealing strip in position.

6. A seam for receptacles comprising flanges on the receptacle parts and a readily removable sealing strip embracing the said flanges, said sealing strip comprising a channel-shaped piece of thin malleable metal, the flanges of the receptacle parts and of the sealing strip being bent to form coincident medial grooves forming interlocking parts which assist in sealing the receptacle and holding the sealing strip in position, the sealing strip being provided with a tongue for stripping the same from engagement with the receptacle flanges.

In witness whereof I have hereunto set my hand in the presence of two subscribing witnesses.

JOHN C. BOWERS
